E. V. CROWELL ET AL
TUBING BLEEDER AND ANCHOR

Filed Jan. 7, 1926

UNITED STATES PATENT OFFICE.

ERD V. CROWELL, OF LOS ANGELES, AND LEONARD A. WATSON, OF TAFT, CALIFORNIA;
SAID LEONARD A. WATSON ASSIGNOR TO SAID ERD V. CROWELL.

TUBING BLEEDER AND ANCHOR.

Application filed January 7, 1926. Serial No. 79,751.

It is the object of this invention to provide a tubing bleeder cooperating with a tubing anchor so that turning the string of tubing will release the anchor to permit its operative engagement when the string of tubing is lowered slightly, the tubing bleeder also cooperating with the tubing anchor so that subsequent lowering of the upper portion of the string of tubing relative to its anchored lower portion will open the bleeder valve.

It is a further object of the invention to provide a tubing bleeder comprising normally expanded telescopic parts fixed against relative turning movement, and having the upper and lower portions of a string of tubing fixed to the respective telescopic parts with a tubing anchor mounted on the lower portion of the string of tubing.

The tubing anchor is released for expansion to operative position by turning that portion of the string of tubing on which it is mounted, and the fixing of the telescopic parts of the bleeder against relative turning movement provides for said turning of the lower portion of the string of tubing by rotation of the upper portion of the string. After release of the anchor it is expanded to operative position by lowering that portion of the string of tubing upon which it is mounted, and said downward movement of the lower portion of the string of tubing may be accomplished by lowering the upper portion of the string, due to the normal expansion of the telescopic parts of the tubing bleeder by yieldable means which exerts sufficient pressure to prevent relative telescoping of the parts of the tubing bleeder when the upper portion of the string is lowered.

The telescoping parts of the tubing bleeder are provided with normally non-aligned ports, and after the anchor operatively engages the casing so as to fix the lower portion of the string of tubing, continued lowering of the upper portion of the string overcomes the resistance offered by the yieldable expansion means and thus telescopes the tubing bleeder so as to align the ports and thus permit escape of fluid from the string of tubing.

The invention will be readily understood from the following description of the accompanying drawings, in which:

Fig. 1 is a partial axial section showing the tubing bleeder closed and the tubing anchor secured in inoperative position.

Fig. 2 is a similar view showing the anchor in operative position and the bleeder shifted to open position.

Fig. 3 is a transverse section on the line 3—3 of Fig. 1.

Fig. 4 is a fragmentary view similar to Fig. 1 but showing a modified form of the tubing bleeder.

Fig. 5 is a partial axial section of a modified form of the tubing anchor.

A usual string of tubing 1 extends downwardly through the casing 2 of a well in spaced relation from the wall of the casing.

In the form of the invention illustrated in Figs. 1 to 3, the combined tubing bleeder and anchor comprises relatively telescoping parts 3 and 4 which constitute the bleeder, and a length of tubing 5 having slips 6 mounted thereon to form the anchor. The part 4 may be connected to the tubing 5 by a threaded connection 7, and the upper end of part 3 and the lower end of tubing 5 are connected by coupling collars 8 and 9 to the ends of next adjacent lengths of the string 80 of tubing 1 so that the bleeder may be positioned at any desired level in the string of tubing.

The parts 5—6 form a usual tubing catcher and anchor of the type adapted for expansion of slips 6, either automatically by sudden dropping of the string of tubing as in the case of breakage, or manually by turning the string of tubing and then lowering the same slightly. As an instance of this arrangement beveled surfaces 10 are formed on the tubing 5 and the slips 6 are carried by a sleeve 11 which is slidable on tubing 5. The slips are expanded by the beveled surfaces 10 when tubing 5 is shifted downwardly relative to sleeve 11, and the engagement of the slips with the wall of casing 2 locks the tubing 5 and the portion of the string of tubing which depends therefrom.

A coil spring 12 is mounted on tubing 5 between the lower end of sleeve 11 and the collar 9, so that the spring is normally compressed by the weight of sleeve 11 and slips 6, thereby positioning the slips in inoperative position below the beveled surfaces 10 as shown in Fig. 1. If the string of tubing

breaks so that it drops suddenly, the spring 12 tends to retard the fall of the slips which are thereby expanded by the beveled surfaces 10 so as to engage the wall of casing 2 and automatically anchor the tubing.

The means for anchoring the tubing manually, irrespective of the operation of the automatic device, comprises a sleeve 13 slideable on tubing 5 below the sleeve 11. A vertical slot 14 opens through the lower end of sleeve 13 and has a transverse slot 14^a at its upper end terminating in a relatively short depending slot 14^b. Lug 15 on the collar 9 is slideable in the slots, and when seated in the slot 14^b limits sliding of tubing 5 relative to sleeve 13 so as to space the sleeves 11 and 13. Bowed springs 16 depend from sleeve 13 and are connected at their lower ends by a collar 17 which is slideable on the string of tubing; and these springs frictionally engage the wall of casing 2 to hold the sleeve 13 against turning in the casing. As a consequence tubing 5 may be turned relative to sleeve 13 so as to move lug 15 along transverse slot 14^a and into alignment with slot 14; and with the parts in this position, lowering the tubing 5 will move lug 15 downwardly in slot 14 and thus shift the sleeve 11 downwardly against the sleeve 13 which is held against longitudinal displacement by its springs 16. Sleeve 11 is thus shifted upwardly so as to slide the slips 6 along the beveled surfaces 10 and thereby expand the slips into engagement with the casing wall 35 for locking tubing 5 and the portion of the string of tubing which depends therefrom.

The telescopic member 4 of the tubing bleeder is a shell having an enlarged bore 18 provided with diametrically opposite longitudinal grooves 19; and the member 3 is a length of tubing having lugs 20 projecting radially from its lower end and seating in the grooves. By this arrangement the part 3 is free to telescope relative to the part 4, but said parts are fixed against relative turning so that rotating the upper portion of the string of tubing and the part 3 which is fixed thereto, will also turn the part 4 and the tubing 5 to release the tubing anchor by 50 alinement of lug 15 with the slot 14.

A sleeve 22 is mounted on tubing 3 and is fixed to shell 4 by threaded connection 23; and a bleeder port 24 in tubing 3 is normally closed by the sleeve. The sleeve is provided 55 with a port 25 adapted for alinement with port 24 when tubing 3 is telescoped relative to sleeve 22 and shell 4; and the bore of sleeve 22 is preferably provided with an elongated annular recess 26 communicating with port 25, so that any appreciable telescoping of tubing 3 will permit fluid to drain through port 24, recess 26, and port 25, without necessitating exact alinement of the ports.

Packing glands 27 are preferably provided

between the ends of sleeve 22 and tubing 3; and a coil spring 28 is mounted on tubing 3 between the upper packing gland and the coupling collar 8, in order to normally yieldably maintain the parts 3-4 in expanded position with port 24 closed. The spring 28 is of sufficient strength to maintain the parts 3-4 in expanded position and thus lower tubing 5 when the upper portion of the string of tubing is depressed, and as a consequence, 75 the tubing anchor after being released by turning the upper portion of the string of tubing, may be shifted to operative position for locking the lower portion of the string of tubing, by slightly depressing the upper portion of the string. With the lower portion of the string of tubing thus locked against axial displacement in the casing, continued depression of the upper portion of the string causes spring 28 to yield, and thereby telescopes the parts 3-4 so as to open port 24 and permit the string of tubing to drain. An interior shoulder 29 formed by the enlargement of the bore of shell 4; is adapted 90 for abutment by the lugs 20 to limit telescoping of the parts 3-4 when the ports 24-25 are in alinement.

After the tubing has drained and it is desired to withdraw the same from the well, the upper portion of the string of tubing is 95 elevated to again expand parts 3-4 and thereby close the bleeder port 24. Continued elevation of the upper portion of the string of tubing causes lugs 20 to engage the lower packing gland 27 and thereby elevate 100 shell 4 and the tubing 5; and the movement of beveled surfaces 10 of the tubing 5 away from slips 6 releases the latter from their locking engagement with casing 2.

In operation, preparatory to running the 105 tubing into the casing bore, the tubing is turned so as to seat the lug 15 in slot 14^b, thereby rendering the manually controlled anchoring means inoperative; and conversely, when pulling the string of tubing from the casing bore, the tubing is preferably turned so as to position the lug 15 in the slot 14, thereby rendering the manually controlled means automatically operative for catching the tubing in the event of breakage, irrespective of the functioning of spring 12 of the automatic catcher, and thus increasing 115 the safety factor of the automatic catcher when pulling tubing.

In the modification of the invention illustrated in Fig. 4, a tubing anchor is employed similar to that already described, and the telescopic part of the tubing bleeder which is fixed to tubing 5 is elongated as shown at 4^a. Instead of the spring 28 previously described, a spring 28^a is mounted in the elongated bore 18^a of shell 4^a between the shoulder 29^a of the bore and lugs 20 of the part 3. The operation is the same as that previously described, the spring 28^a 130

normally maintaining the parts 3—4^a in expanded position, but yielding after the tubing anchor locks the lower portion of the string of tubing, to permit telescoping of said parts for alinement of ports 24 and 25.

With either form of the tubing bleeder, it will be noted that if the tubing breaks and the slips 6 are consequently automatically expanded to lock the lower portion of the string of tubing in the casing, the spring 28 or 28^a will cushion the fall of the upper portion of the string of tubing and thereby prevent injury to the tubing.

In the modification of the invention illustrated in Fig. 5, a tubing anchor is employed which can only be manually operated and therefore does not form an automatic catcher in the event of breaking of the tubing. As an instance of this arrangement the tubing bleeder may be either of the constructions previously described, and the telescopic member which is fixed to tubing 5 is preferably an integral part thereof as shown at 4^b. The slips 6 cooperate with the beveled surfaces 10 for expansion of the slips, but instead of employing the sleeves 11 and 13 and the spring 12, the slips are supported directly by a sleeve 13^b which is provided with the friction springs 16, and the tubing 5 is adapted for turning and longitudinal movement relative to sleeve 13^b, as previously described, to lock the slips in the well casing.

We claim:

1. A string of tubing comprising relatively telescopic upper and lower portions of the string having normally non-alined ports adapted for alinement by telescoping of the parts, and means for anchoring the lower portion of the string of tubing at any desired level in the well.

2. A string of tubing comprising relatively telescopic upper and lower portions of the string having normally non-alined ports adapted for alinement by telescoping of the parts, and a combined tubing catcher and anchor adapted to automatically secure the lower portion of the string of tubing against dropping in a well in the event of breaking of the tubing and arranged for manual actuation to anchor the lower portion of the string of tubing at any desired level in the well.

3. A string of tubing comprising relatively telescopic upper and lower portions of the string fixed against relative turning movement and having normally non-alined ports adapted for alinement by telescoping of the parts, and normally inoperative means for anchoring the lower portion of the string of tubing in a well, said anchoring means being released for operation by turning the string of tubing relative thereto.

4. A string of tubing comprising relatively telescopic upper and lower portions of the

string having normally non-alined ports adapted for alinement by telescoping of the parts, means for anchoring the lower portion of the string of tubing in a well, said anchoring means being operated by depression of the lower portion of the string of tubing relative to the anchoring means, and yieldable means normally maintaining the telescopic parts in expanded position to permit said depression of the lower portion of the string of tubing by lowering the upper portion of the string, said expanding means being adapted to yield by lowering the upper portion of the string of tubing after anchoring of the lower portion of the string to permit telescoping of said parts.

5. A string of tubing comprising relatively telescopic upper and lower portions of the string fixed against relative turning movement and having normally non-alined ports adapted for alinement by telescoping of the parts, normally inoperative means for anchoring the lower portion of the string of tubing in a well, said anchoring means being released for operation by turning the string of tubing relative thereto, said anchoring means being operated by depression of the lower portion of the string of tubing relative to the anchoring means, and yieldable means normally maintaining the telescopic parts in expanded position to permit said depression of the lower portion of the string of tubing by lowering the upper portion of the string, said expanding means being adapted to yield by lowering the upper portion of the string of tubing after anchoring of the lower portion of the string to permit telescoping of said parts.

6. A string of tubing comprising relatively telescopic upper and lower portions of the string, means for automatically securing the lower portion of the string of tubing against dropping in a well in the event of breaking of the tubing, and yieldable means normally expanding the telescopic parts and adapted to yield for cushioning the fall of the upper portion of the string of tubing in the event of said anchoring of the lower portion of the string.

7. A string of tubing comprising relatively telescopic upper and lower portions of the string having normally non-alined ports adapted for alinement of telescoping of the parts, a combined tubing catcher and anchor adapted to automatically secure the lower portion of the string of tubing against dropping in a well in the event of breaking of the tubing and arranged for manual actuation to anchor the lower portion of the string of tubing at any desired level in the well by depression of the lower portion of the string of tubing relative to said anchoring means, and yieldable means normally maintaining the telescopic parts in expanded position to permit said depression of the

lower portion of the string of tubing by lowering the upper portion of the string, said expanding means being adapted to yield by lowering the upper portion of the string 5 of tubing after anchoring of the lower portion of the string to permit telescoping of said parts, and said expanding means being also adapted to yield for cushioning the fall of the upper portion of the string of tubing 10 in the event of the lower portion of the string of tubing being secured against dropping in the well by automatic operation of the tubing catcher.

8. A string of tubing comprising relatively 15 telescopic upper and lower portions of the string fixed against relative turning movement and having normally non-alined ports adapted for alinement by telescoping of the parts.

20 9. A string of tubing comprising relatively telescopic upper and lower portions of the string adapted for flow of fluid through the string of tubing and having normally non-alined ports spaced above the fluid inlet 25 to the string and adapted for alinement by telescoping of the parts to bleed the string of tubing of fluid, and yieldable means normally maintaining the telescopic parts in expanded position.

30 10. A string of tubing comprising relatively telescopic upper and lower portions of the string fixed against relative turning movement and having normally non-alined ports adapted for alinement by telescoping 35 of the parts, and yieldable means normally maintaining the telescopic parts in expanded position.

11. A string of tubing comprising relatively telescopic upper and lower portions of 40 the string, and means for anchoring the lower portion of the string at any desired level in a well.

12. A string of tubing comprising relatively telescopic upper and lower portions 45 of the string, and a catcher adapted to automatically secure the lower portion of the string against dropping in a well in the event of the breaking of the tubing.

13. A string of tubing comprising relatively 50 telescopic upper and lower portions of the string, and a combined tubing catcher and anchor adapted to automatically secure the lower portion of the string against dropping in a well in the event of breaking of the 55 tubing and arranged for manual actuation

to anchor the lower portion of the string at any desired level in the well.

14. A string of tubing comprising relatively telescopic upper and lower portions of the string fixed against relative turning 60 movement, and normally inoperative means for anchoring the lower portion of the string of tubing in a well, said anchoring means being released for operation by turning the string of tubing relative thereto. 65

15. A string of tubing comprising relatively telescopic upper and lower portions of the string, means for anchoring the lower portion of the string of tubing in a well, said anchoring means being operated by depression of the lower portion of the string of tubing relative to the anchoring means, and yieldable means normally maintaining the telescopic parts in expanded position. 70

16. A string of tubing comprising relatively telescopic upper and lower portions of the string fixed against relative turning movement and having normally non-alined ports adapted for alinement by telescoping of the parts, said alined ports being adapted 80 to bleed the string of tubing of fluid.

17. A string of tubing comprising relatively telescopic upper and lower portions of the string adapted for flow of fluid through the string and fixed against relative turning movement and having normally non-alined ports spaced above the fluid inlet to the string and adapted for alinement by telescoping of the parts to bleed the string of tubing of fluid, and yieldable means normally 90 maintaining the telescopic parts in expanded position. 95

18. A string of tubing comprising relatively telescoping upper and lower portions of the string, a catcher adapted to automatically secure the tubing against dropping in a well in the event of breaking of the tubing, and manually controlled means for anchoring the tubing at any desired level in a well, said anchoring means being 100 adapted to be shifted to a position where it will become automatically operative in the event of dropping of the tubing to augment the safety factor of the automatic tubing catcher. 105

In testimony whereof we have affixed our signatures to this specification.
